CLAIM

The ornamental design for a weight plate, as shown and described.

DESCRIPTION

FIG. 1 is a perspective view of a weight plate showing my new design, the bottom perspective view being a mirror image;

FIG. 2 is a top plan view thereof;

FIG. 3 is a bottom plan view thereof, which is a mirror image of the top plan view;

FIG. 4 is a left side elevational view thereof;

FIG. 5 is a right side elevational view thereof, which is a mirror image of the left side elevational view;

FIG. 6 is a front elevational view thereof; and,

FIG. 7 is a rear elevational view thereof, which is a mirror image of the front elevational view.

1 Claim, 6 Drawing Sheets
